US0D1114047S

(12) **United States Design Patent** (10) **Patent No.:** **US D1,114,047 S**
(45) **Date of Patent:** **** Feb. 17, 2026**

(54) **TRIPOD WITH A FILL LIGHT**

(71) Applicant: **Shenzhen Leaderment Technology Co., Ltd.**, Shenzhen (CN)

(72) Inventor: **Chunbin Li**, Shenzhen (CN)

(73) Assignee: **Shenzhen Leaderment Technology Co., Ltd.**, Shenzhen (CN)

(**) Term: **15 Years**

(21) Appl. No.: **29/858,196**

(22) Filed: **Oct. 28, 2022**

(51) **LOC (15) Cl.** **16-05**

(52) **U.S. Cl.**

USPC **D16/244**; D26/104

(57) **CLAIM**

The ornamental design for a tripod with a fill light, as shown and described.

DESCRIPTION

FIG. 1 is a front and top perspective view of a tripod with a fill light, showing my new design;

FIG. 2 is a rear and bottom perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof; and,

FIG. 9 is an exploded view thereof.

The dashed lines in the figures illustrate portions of the tripod with a fill light that form no part of the claimed design.

1 Claim, 9 Drawing Sheets
